UNITED STATES PATENT OFFICE

GILBERT MICHEL, OF BAGNEUX, FRANCE, ASSIGNOR TO SOCIETE "LE MAGNESIUM INDUSTRIEL", OF PARIS, FRANCE

PROCESS OF PREPARING MOLDING SANDS FOR EASILY OXIDIZABLE METALS SUCH AS MAGNESIUM

No Drawing. Application filed March 24, 1928, Serial No. 264,579, and in France July 5, 1927.

My invention relates to a process for the preparation of foundry sand.

In casting metals, it is usual to mix vegetable and mineral products of various kinds

5 with foundry sand either for improving the porosity of the molds, by their mere presence, by imparting sufficient plasticity and solidity to the sand mixture, or for producing, under the action of the heat from the metal being 10 poured, an emission of gas, the said gas constituting and facilitating the ventilation of the mold or forming a neutral atmosphere insulating the cast metal from the mold and from the exterior atmosphere.

15 Such additions give very unsatisfactory results or failures, when casting easily oxidizable metals and especially metals such as magnesium which have a very great affinity for water contained in the material of which 20 molds are made, and for oxygen and nitrogen.

Likewise as is known many attempts have been made to overcome these disadvantages, by mixing with the sand, certain vegetable 25 products, such as resins, gums, rubber, certain salts and the like. All these products are either relatively high priced or do not easily give a sufficient homogeneity of the foundry sand, so that the results obtained 30 are, in general, rather unsatisfactory.

My invention consists essentially in working up the sand for the molds, and when necessary that of the cores, with a suitable addition of pulverized graphite preferably 35 mixed with more or less of an aqueous solution of ammonia.

In molds involving a large quantity of sand, it is moreover necessary to thus prepare all of the sand for the mold, because in 40 general it will suffice to provide a layer of graphite sand, several centimeters in thickness, around the pattern, the rest of the mold or cores can then be made of old sand, for example.

45 In making molds destined to be poured

green, the proportion of ammonia must be greater than is necessary in making baked molds. The ammonia may even be completely eliminated in the latter.

For making voluminous or complex molds 50 necessitating a certain period of manipulation, the ammonia can be diluted with a sufficient quantity of water to eliminate too rapid evaporation of the ammonia water and conserve a sufficient plasticity during the whole 55 molding period.

I can likewise add to the mixture, the ordinary agglomerants of commerce for increasing plasticity.

This process provides at least in the thickness of sand capable of being in contact with the fused metal, a sand which is sufficiently anhydrous and permeable to be without action on the fused metal, and more particularly in connection with easily oxidizable 65 metals.

As a final precaution, the parts of the mold with which the hot metal will come into contact, can be coated over with a mixture of pulverized graphite and ammonia water. 70 This coating moreover gives the cast metal an extremely brilliant aspect and does not produce, as is generally the case, a more or less oxidized surface.

A number of examples will now be given 75 in which good results have been obtained.

In making a baked mold or a green mold, for casting magnesium the following materials and proportions may be employed:

	Kgs.
White silicious sand (dry weight)---	30
Ordinary yellow sand (dry weight) --	12
Naphthalene (pulverized)-----	0.600
Graphite (pulverized)-----	0.500
Ordinary agglomerants of commerce--	0.620

The complementary plasticity of this sand is obtained either by an ammoniacal solution or by the addition of common water, when making a baked mold. For making a green 90

Preferably, the power plant of the plane consists of two motors as above explained, and preferably each of these motors will develop one-half the total power required to 5 navigate the ship. About one-half the total power will be usually required to sustain the weight of the plane and the other half will be required for propulsion and traction as well as for ascending. In the event of the 10 failure of one motor, power developed by the other will be amply sufficient to enable the pilot to maintain control and altitude until a suitable landing place can be located.

It is not intended to limit the opposing sections of each wing to a single pair as four or 15 more wing sections may be employed if desired. It will be pointed out that the rotating wings are rotated in opposite directions so that the torque will be neutralized. It 20 will be further pointed out that the rotating wings interdigitate or mesh during rotation. However, it is not intended to limit the wing construction to intermeshing wings, since the wings may be spaced far enough apart so that 25 they do not overlap, if desired.

In operation, the pitch of the wing sections is varied for traction as well as for ascent and descent. The pitch angle, of course, must be positive for taking off, but for landing it need not necessarily be negative since 30 the engines may be throttled down until the lifting force of the wings is decreased to less than the weight of the plane and it may then descend at a speed in proportion to the force 35 resisting it. In case of a dead stick landing, it will be necessary to set the wings to a negative angle of probably four or five degrees so they will auto-rotate.

The variable pitch wing construction is of 40 equal importance for traction purposes in a horizontal direction. Since the pitch which is efficient for ascent or descent is comparatively flat and therefore devoid of thrust in a horizontal direction, it is necessary to use 45 the maximum pitch for horizontal flight partly to compensate for the air speed and partly to utilize all of the available motor power not utilized for sustaining the weight of the plane. In addition to using the maximum pitch of the wings, the angle of incidence of the wings must be increased, as 50 shown by dotted lines in Fig. 2, that is, the wings must be inclined forward until the vertical component of thrust will just sustain the plane and the balance of the thrust 55 will be utilized for traction.

From the above description, it is thought 60 that the construction and operation of the invention will be clearly understood without further explanation.

Having thus described the invention, I 65 claim:

1. In a helicopter, a rotary sustaining wing including a tubular beam, wing sections swiveled on the ends of the beam, a steel cable

housed in the beam and connected to said sections for equalizing the thrust of the sections on the beam, and means for varying the pitch of said sections on the beam.

2. In a helicopter, a rotary sustaining wing 70 comprising a tubular beam, an axle secured to the beam for rotating the beam, opposed wing sections swivelly mounted on the ends of the beam, a cable housed in the beam and connecting said sections together, and a sliding sleeve on said axle operatively connected to the trailing edges of said sections for changing the pitch angle of the sections on said beam.

3. In a helicopter, a rotary sustaining wing 75 including a tubular beam, opposed wing sections swiveled on the ends of said beam, an axle secured to substantially the center point of the beam for rotating the beam, the inner ends of said sections being curved in the arc 80 of a circle struck from said axle as a center, a steel cable loosely housed in said beam and rigidly secured at the ends to said sections, and tubular housings carried by said sections and pivotally receiving the ends of said beam, 85 said cable equalizing thrust of said beam on said housings due to centrifugal force exerted by said sections.

4. In a helicopter, a rotary wing including 90 a tubular beam, wing sections swiveled on the ends of said beam at substantially the centers of pressure of the sections, tubular housings carried by the sections and pivotally receiving said beam, and a cable housed within the beam and rigidly secured at the ends to 95 said sections for equalizing the centrifugal thrust of said sections on the beam and housings thereof.

5. In a helicopter, a rotary wing comprising 100 a tubular beam, wing sections of substantially identical structure as to camber, chord and bracing ribs, tubular housings carried within the internal structure of said wing sections and housing the ends of said beam, and a steel cable trained through said beam and rigidly secured to said sections.

6. In an airship, a fuselage, a truss projecting from opposite sides of the fuselage, 105 rotary wings extending normally horizontally 110 above the fuselage and carried by the ends of said truss, means for swinging the truss pendulum-like to tilt said wings and change the angle of incidence or thrust thereof, each wing comprising pivotally mounted opposing sections, and means operable independently 115 of said truss for changing the thrust angle of said sections.

7. In an airship, a fuselage, a control wheel 120 therein, rotary wings carried by the fuselage and each comprising a beam and swivel opposing wing sections on the ends of the beam, axles carried by said beams midway 125 between the wing sections thereof, sliding sleeves on said axles operatively connected to the trailing edges of said wing sections, a 130
